UNITED STATES PATENT OFFICE.

ARTHUR W. SUITER, OF WOONSOCKET, RHODE ISLAND, ASSIGNOR TO RUSSIA CEMENT COMPANY, OF GLOUCESTER, MASSACHUSETTS, A CORPORATION OF MASSACHUSETTS.

BOTTLE-CAP SORTING AND FEEDING MECHANISM.

Original application filed May 4, 1921, Serial No. 466,822. Divided and this application filed April 1, 1922, Serial No. 542,777.

To all whom it may concern:

Be it known that I, ARTHUR W. SUITER, a citizen of the United States, residing at Woonsocket, in the county of Providence and State of Rhode Island, have invented new and useful Improvements in Bottle-Cap Sorting and Feeding Mechanism, of which the following is a specification.

This invention relates to mechanisms for sorting bottle caps positioned indiscriminately in a supply hopper so that they may be presented successively in proper position to bottle capping mechanism.

This application is a division of application Serial No. 466,822 filed May 4, 1921 for machines for operating on bottles.

Referring to the drawings,

Figure 1 is a right side elevation of the upper portion of the complete machine showing the cap sorting and feeding mechanism in position thereon.

Figure 2 is a section on line 2—2 of Figure 1.

Figure 3 is a fragmentary section at right angles to Figure 2 and with parts removed.

Figure 4 is a fragmentary detail of the cap sorting mechanism.

Figure 5 is a detail section of the cap distributing hopper.

The cap sorting and distributing mechanism is mounted in inclined position on a bracket 180 fixed to the top frame member 181 of the machine, an inclined shaft 182 being journaled in the bracket 180 and carrying a rotating hopper at its outer end. As shown in Figure 2, the shaft 182 has fixed on its outer end a disk 183, to one face of which is fixed a bevel gear 184. This gear meshes with a bevel pinion 185 carried

on a shaft 186 which is journaled in the bracket 180 and carries at one end a belt pulley 187, by which it may be rotated by a belt 188 passing thereover. A ratchet mechanism 187' between the belt pulley and shaft 186 allows the shaft to be turned by hand in its normal drive direction without affecting the belt pulley.

Fixed to the bracket 180 surrounding the shaft 182 is a spider 190 which supports the upper end of a stationary arcuate raceway section 191. This raceway section has a passageway 192 between inner and outer walls 193 and 194

thereof of sufficient size to accommodate a single line of caps and connects near its lower end with the upper end of a raceway 55 195 which projects downwardly to mechanism for fixing the caps to bottles. The caps are placed in a hopper comprising a cylindrical drum 196 fixed to rotate with the disk 183. This drum is composed of a cylinder 60 197, preferably of glass, or mesh wire, engaging at its inner end in a recess in a ring member 198 and at its outer end in a similar recess in a cap member 199, these parts being held assembled by means of tie bolts 200 extending between the ring and the cap. Fixed between the disk 183 and the ring 198 are a series of fingers 201 spaced apart sufficiently 65 to permit a cap to pass therebetween and between the ring and the disk. These spaces 70 are radial to the disk 183 at their inner ends but are turned backwardly with relation to the direction of rotation of the hopper at their outer ends so that they may discharge the caps into the raceway at positions 75 considerably above the lowest part of the hopper and where they are not subjected to interference by the mass of caps agitated by the turning of the hopper. In order to insure that the caps may be passed there- 80 through properly presented to the raceway, the plate 183, ring 198, and the fingers are laterally bent, as shown more particularly in Figure 5, to form crooked passageways, so that the ring 198 presents an annular 85 ridge at 202. This ridge is cut away, as shown in Figure 4 and in dotted lines in Figure 5, at 203, to present a series of outwardly directed points. If the caps are properly presented, their hollow sides facing 90 the ring 198, these projections may enter the hollows, and the caps may pass outwardly between the plate and ring and between the fingers into the raceway 191. Should caps be presented reversely positioned, these 95 points form obstructions which engage the tops of the caps and prevent them from passing to the raceway. As the hopper rotates, the misdirected caps, on reaching their upper positions, are returned to the hopper 100 by gravity. Also any caps in excess of those required to fill the raceway are permitted to return through the passageways between the fingers, a blade 204 inclined from the

outer edge of the raceway section 191 to the circumferences of the disk 183 and the ring 198 serving to push inwardly any slightly protruding caps which might otherwise tend to jam. A notched circular plate 183' is preferably centrally secured to the inner face of plate 183 to help agitate the caps as the hopper rotates, and tends to position them for entry in the passageways between the fingers.

From this description it will be evident to those skilled in the art that many modifications and changes may be made without departing from the spirit or scope of the invention as defined in the appended claims.

I claim:

1. A distributing mechanism for bottle caps comprising a receptacle adapted to contain caps and having an escape passage for said caps, said escape passage extending angularly, and a pointed projection in said passage over which a cap may pass when it is presented with its hollow side facing thereto but preventing the passage of a cap reversely presented.

2. A distributing mechanism for bottle caps comprising a hopper having a series of passageways for the caps, and a projection within each of said passageways engageable within the open side of a cap properly presented therein and permitting said cap to pass, and engageable with the top of

an improperly presented cap to prevent its passage.

3. A distributing mechanism for bottle caps comprising a member having a passageway for the caps, a pointed projection within said passageway engageable within the open side of a cap properly presented therein and permitting said cap to pass, and engageable with the top of an improperly presented cap to prevent its passage, and means for removing protruding caps from said passageways.

4. A mechanism of the class described, comprising a rotary drum for containing bottle caps, a disk member forming the base of said drum, a ring member fixed to the side of said drum, spacing elements between said ring and disk to define therewith channels for the escape of caps, said members and elements being laterally bent to cause said channels to be crooked, and a pointed projection extending from one of said members at the bend of each channel, over which a cap may pass when its hollow side is facing said member, but preventing the passage of a cap reversely presented, and a raceway for receiving the caps passing through said channels.

In testimony whereof I have affixed my signature.

ARTHUR W. SUITER.
